Patented Feb. 26, 1918.

Louis J. Gonyea
Inventor

By *Geo. P. Kimmel.*

Attorney

UNITED STATES PATENT OFFICE.

LOUIS J. GONYEA, OF SPOKANE, WASHINGTON.

TRAY.

1,257,843.

Specification of Letters Patent. Patented Feb. 26, 1918.

Application filed March 9, 1917. Serial No. 153,716.

To all whom it may concern:

Be it known that I, LOUIS J. GONYEA, a citizen of the United States, and resident of Spokane, in the county of Spokane and 5 State of Washington, have invented certain new and useful Improvements in Trays, of which the following is a specification.

The present invention relates to the class of kitchen and table articles, and has particular reference to new and useful improvements in trays.

My invention relates to an improved holder or receiver on which to place bread, cake and the like to cool when received from 15 the baking oven, and its construction and arrangement of parts are such that air may as readily pass to and reach the bottom of the cake or the like which rests on the holder as to the top or sides thereof.

20 The primary object of the invention is to provide a novel tray of the character described, that is of a portable nature, efficient in operation, and strong and durable in use.

A still further object of the invention is 25 to provide an apparatus in which the parts thereof are closely assembled, and combined, thereby taking up a minimum amount of space.

Other improvements and novel details in 30 the construction and arrangement of the various parts of the apparatus will be brought out more in detail in the description to follow, which, for a clear understanding of the invention, should be considered in connection with the accompanying drawing, forming a part hereof, and wherein is disclosed, for the purpose of illustration, convenient and satisfactory embodiments of the invention. It is to be noted, 35 in this connection, that minor changes in the construction and arrangement of the parts may be made without departing from the spirit of the invention or the principle of operation of the various parts.

40 In the drawing:

Figure 1 is a perspective view of my invention, the side trays thereof being extended;

Fig. 2 is a longitudinal sectional view of 45 my invention with the trays in closed position, and

Fig. 3 is a perspective view of the supporting and guiding frames associated with the body portion.

50 Corresponding and like parts are referred to in the following description and indi-

cated in all the views of the drawing by the same reference characters.

My improved tray comprises a substantially rectangular wire frame 1 having supporting means connected to the corners thereof. The supporting means comprises U-shaped wire members 2, the free ends thereof being coiled about the frame 1, as indicated at 3. The body of my invention 65 comprises a reticulated material member 4, preferably of wire, for an obvious purpose.

Opposite sides of the frame member are provided with a pair of supporting guiding flanges designated F in their entirety for a 70 purpose which will hereinafter be described in detail. The said guiding flanges comprise a sheet metal body portion 5 having oppositely disposed laterally extending flanges 6 and 7. Intermediate the edges of 75 said member I provide a laterally extending flange 8 in parallel relation with the flanges 6 and 7 and extending in the same direction with the lower flange.

The tray members of my invention comprise a substantially rectangular wire frame member 9 having a surface 10 of reticulated material to supply the desired supporting surface for the cake, bread, or like article to be cooled. In order to provide the desired rigidity for the supporting trays when the same are extended a wire body member 11 is provided having laterally extending arms 12, the free ends of which are coiled about the said frame providing the desired 85 supporting member. As the construction of both tray members are identical the description of one is thought to suffice. Wire handle members 12' are provided on the outer edges of said trays forming means for 90 withdrawing the same from closed position. Handles 13 and 14 are provided on the main body portion and are attached to the wire frame 1 to provide means for raising the entire device.

100 From the foregoing, it will be readily understood by those skilled in the art that I have provided an exceedingly efficient and simple holder for receiving hot bread, cakes, and other articles and permitting the same to cool for a period of time subsequent to their removal from an oven or other form of stove. The holder due to the provision of the reticulated material will permit a circulation of air between the same and the 110 bottoms of the articles supported thereon. Obviously, the frame 1 serves as one support

while the slideable frames 9 afford other supports, thereby permitting a plurality of objects to be arranged upon the holder for cooling. However, when not using the slideable supports 9, the same may be telescoped in the frame 1 due to their engagement with the guiding flanges, thereby providing a compact device. By providing the arms 12, it will be readily understood that the outer ends of the slideable shelves 9 will be effectually supported when arranged in extended positions, thereby preventing undue tilting or tipping of the main frame 1. The holder may be readily moved from place to place by means of the handles 12', 13 and 14 arranged therein.

I claim:

1. In a device of the character described, a main frame, a foraminated covering for said main frame, channeled guide elements secured to the opposite sides of the main

frame, secondary frames slidably engaged in said channeled members and arranged in superposed relation, foraminated covers for said secondary frames, and depending supporting arms secured to the outer ends of the secondary frames.

2. The combination of a rectangular wire member, U-shaped wire legs attached thereto, supporting guiding frames mounted on opposite sides of said body comprising, a body portion, oppositely disposed laterally extending flanges formed on the upper and lower edges thereof, and a flange parallel with last-mentioned flange formed on the same side of said body intermediate the edges thereof, trays slidably mounted on the said flanges, and supporting means mounted on said trays for a purpose specified.

In testimony whereof, I affix my signature hereto.

LOUIS J. GONYEA.
